FLUSH TANK TOP

Clifton I. Panciera, Washington, D. C.

Application April 6, 1955, Serial No. 35,381

Term of patent 14 years

(Cl. D4—5)

Figure 1 is a front elevational view of a flush tank top embodying my new design;

Figure 2 is a top plan view thereof;

Figure 3 is an end elevational view of the same;

Figure 4 is a vertical sectional view of the same, as seen on line 4—4 of Figure 2;

Figure 5 is a similar view as seen on line 5—5 of Figure 2, and

Figure 6 is a horizontal sectional view as seen on line 6—6 of Figure 1.

I claim:

The ornamental design for a flush tank top, as shown.
